(57) **CLAIM**

The ornamental design for a case for electronic communications device, as shown and described.

DESCRIPTION

FIG. 1 is a front perspective view of a case for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detail view of the encircled region of FIG. 2.

The dot-dash broken line circles in FIGS. 2 and 9 delineate a portion of the case for electronic communications device that is part of the claimed design and that is shown on an enlarged scale in FIG. 9. Except for the solid-line interior portions of the openings and button regions, the interior surfaces of the case shown in FIGS. 1 and 3 and the dashed broken line shown in FIG. 1 form no part of the claimed design.
